UNITED STATES PATENT OFFICE.

CHARLES REESE, OF BALTIMORE, MARYLAND.

RAILWAY-RAIL JOINT.

SPECIFICATION forming part of Letters Patent No. 224,476, dated February 10, 1880.

Application filed September 17, 1879.

To all whom it may concern:

Be it known that I, CHARLES REESE, a citizen of the United States, residing at Baltimore, in the county of Baltimore and State 5 of Maryland, have invented certain new and useful Improvements in Railway-Rail Joints, of which the following is a specification.

My invention relates to an improvement in the ordinary lap or scarf joint for track-rails, 10 the object being to prevent as far as possible the jarring and crushing of the rails caused by the passage of the wheels over the joints where the rails are not laid evenly or settle unevenly.

15 It is well known that a perfectly close joint cannot be maintained at the point where two rails come together, owing to the required allowance for expansion and contraction, and this necessary looseness renders it very difficult to keep the rails on the same level. The consequence is that, whether the joint be a "lap" or a "butt," the wheel, in jumping from the higher to the lower, will batter the rail, and in passing from the lower to the higher 25 will crush the end of the latter. In either case there is a severe jolting, which is injurious to both the cars and the passengers.

My invention seeks to obviate these difficulties by cutting the ends of the rails in the 30 usual way to form a lap or scarf joint, and then beveling or rounding down the top of the tongue of the lap. To better adapt the rail to this form of joint, and to receive the fish-plates, I also make some alterations in 35 the form of the rail, all of which will be more fully hereinafter set forth.

In the drawings, which serve to illustrate my invention, Figure 1 is a perspective view of the joint. Fig. 2 is a longitudinal vertical 40 section taken a little to one side of the center. Fig. 3 is a transverse section taken through the joint. Fig. 4 is a modification illustrating the application of my invention to a scarf-joint.

45 Let A B represent portions of a track-rail, which may be of steel or iron. In the present instance it is a modification of the ordinary T-rail. These rails are gained or halved at the ends for a considerable distance to

form a lap-joint, of which a b are the tongues 50 or laps. D D are fish-plates, arranged on each side of the web and bolted through and through, as shown.

I bevel or round off the tips of the laps at c c. The amount of bevel or reduction will 55 vary according to circumstances; but from one-eighth to one-fourth of an inch will be sufficient for ordinary T-rails.

It will be observed that the beveling commences, or may commence, about midway of 60 the joint, in which case it will not appear at the center, where the section in Fig. 3 is taken. I prefer to bevel down each lap gradually from about the center of its length.

When thus constructed the wheel will ride 65 smoothly over the joint, even when one rail has settled considerably, provided the beveled-down extremity is still curved and protected by the shoulder of the rail where it abuts.

70 As a further precaution against excessive maladjustments of the rails, I may slightly bevel the shoulder also, as indicated at d in Fig. 2.

To compensate for the weakening of the web 75 by splitting it at the joint, I propose to thicken it, without adding to the weight of the rail, by narrowing the tread correspondingly; and to give additional strength and rigidity to the joint I provide a step or shoulder at e e on 80 the base g, and construct the fish-plates to fit snugly between the under side of the head and the shoulders e e, so as to form a support for the head at the joint.

In Fig. 4 I have shown the application of 85 my invention to a scarf-joint. This joint is, however, objectionable, as the thin end of the inside lap is apt to become bent away from the rail and catch the flange of the wheel.

My invention is adapted to all forms of rails, 90 whether for steam-roads or tramways, and for split as well as solid rails.

Having thus described my invention, I wish it understood that I make no claim to a lap or scarf joint for rails, as I believe these are 95 not new with me; and I am also aware that rounded splice-blocks gained or halved into the rails and projecting above the general

level of the same at their centers have been employed, and make no claim to these; but what I do claim is—

1. A lap or splice joint for track-rails in which the ends of the laps are beveled or rounded off, as at *c c*, substantially as and for the purposes set forth.

2. A lap or splice joint for track-rails in which the ends of the laps are beveled or rounded off, as at *c c*, and the shoulders

against which they abut rounded off, as at *d*, substantially as and for the purposes set forth.

In witness whereof I have hereunto signed my name in the presence of two subscribing witnesses.

CHARLES REESE.
